UNITED STATES PATENT OFFICE.

EDUARD MAREK v. MARCHTHAL, OF VIENNA, AUSTRIA-HUNGARY, ASSIGNOR TO
SIEMENS & HALSKE A. G., OF BERLIN, GERMANY, A CORPORATION OF GERMANY.

METHOD OF PRODUCING JUSTIFICATION SYMBOLS IN REGISTER-BANDS.

1,159,694.

Specification of Letters Patent.

Patented Nov. 9, 1915.

Original application filed April 20, 1912, Serial No. 692,158. Divided and this application filed November 25, 1913. Serial No. 802,968.

To all whom it may concern:

Be it known that I, EDUARD MAREK v. MARCHTHAL, a citizen of the Austrian Empire, and residing at Vienna, Austria-Hungary, have invented certain new and useful Improvements in Methods of Producing Justification Symbols in Register-Bands, of which the following is a full and clear specification.

- 10 My invention relates to a method of punching perforated symbols in register bands, having error symbols, for operating, writing, type-setting and type-casting machines, and apparatus therefor.
- 15 When register or perforated bands are made for operating type-writing, type-setting and type-casting machines, the so-called justification values requisite for justifying the lines are obtained only after the text has
- 20 been symbolically represented by perforations in the band; correspondingly, the justification symbols are frequently punched at the ends of the perforated lines. This operation necessitates that the perforated
- 25 band for the second writing or other operation with justified lines be introduced with its rear end first into the typewriting or other machine to be controlled by it, and that it be so employed therein that the bot-
- 30 tom end of a column must be cast or written first. As is well known, this is connected with various disadvantages, particularly relative to the further employment of the written matter. In endeavoring to ob-
- 35 viate these disadvantages devices have been proposed such that the lines which are to be cast can be made by perforated bands moving in the same direction as that in which the perforated band moves when be-
- 40 ing made. In the one type of these devices two punching devices and two perforated band feed-mechanisms are provided in the machine for making the perforated bands; in another type there are two reading de-
- 45 vices and two perforated band feed-mechanisms in the casting machine; in a third form provisional space symbols are punched in the bands, and, after the end of the per-
- 50 forated lines representing the text have been finished, supplemented in a separate punching and band feed-mechanism to form final justification symbols; in a fourth known

form the supplementary perforations are automatically made in a separate machine during the winding of the band. All these known forms necessitate two punching or reading devices and two perforated band feed-mechanisms.

A primary object of my invention is to attain the end in view, *i. e.* to bring the justification symbols to the beginning of the lines, with only the punching mechanism and two perforated band feed-mechanisms, by which the justification symbols are placed at the beginning of the perforated line of text. Besides there being only one punching mechanism this arrangement has the additional advantage that title lines can be arranged exactly in the middle of the line by punching at the beginning of the line corresponding perforated symbols which are ascertained when the text is first written.

My invention is based on the idea of punching through the doubled perforated band in order to save punching mechanism, that part of the band which for the time being is stationary being automatically provided with an error symbol, preferably when the perforated band feed-mechanism is being changed, so that the perforations occur when punching the other parts of the band which are driven past are rendered inoperative at this place. The error symbol requisite for my improved process preferably consists of as many holes as rows of perforations are employed for forming the symbols.

In my Patent No. 1,082,642, of Dec. 30, 1913, from which the present application is divided, I have described and claimed the apparatus by which the desired result is obtained.

The accompanying drawings show one form of apparatus for carrying into practice my improved process by means of an electrically driven machine for making the register-band comprising a rotating type-wheel for printing a control text, the register band being arranged for a six-hole combination.

One main group of switches is provided for bringing about the main operations and an auxiliary switch for bringing about all the other less frequent operations by clos-

ing circuits of corresponding controlling magnets. In addition, for avoiding numerous mechanisms which are otherwise required the rotatory motion between two stoppages of the type-wheel is utilized for adjusting the justification device, the printing and feed corresponding to these positions of the type-wheel being automatically prevented.

10 In said drawings: Figure 1 is a front sectional elevation showing the punching device, Fig. 2 a side sectional elevation of the same, and Fig. 3 a vertical section taken on the line A—B in Fig. 2, Fig. 4 shows a part 15 of the feed mechanism at the moment when the loose loop is pushed forward by hand, and Fig. 5 a portion of a perforated band having text and justification holes.

10 Referring to the drawing, the punching device of the machine for making the register band is arranged between two frame- 20 plates 2 mounted to rock about an axle 1. This device comprises an upper portion 8 (Fig. 3) containing the matrices and a lower 25 portion 7 in which are guided the punch pins 15 provided with catches or pushers 17 (Fig. 3). In the slit or gap between the upper part 8 and the lower part 7 is a thin metal strip 9 which is perforated in the path 30 of the punches and terminates at one side in the guide bar 22. The slit is thus divided into two parts; the register band 100 to be punched is led into the lower part and after being taken around the guide bar 22 is led 35 back through the upper part of the slit. The band 100 is fed forward in the lower half of the slit by two feed wheels 11 and 12 (Figs. 2 and 3) which, together with a ratchet wheel 5, are fast on an axle 3, and in 40 the upper half of the slit by the feed wheels 13, 14 which, together with a ratchet wheel 6, are fast on an axle 4. The thickness of the guide 22 and its distance from the punches 15 are such that the paper loop 1 45 (Fig. 3), formed by the band being drawn taut, corresponds with that length of register band which is necessary for accommodating the justification symbols of one line of text. The two ratchet wheels 5 and 6 50 are secured in their positions for the time being by means of rollers 67, 68 (Fig. 4) resiliently mounted on the plates 2 and are rotated by means of pawls 20, 21 rotatable about axles 23, 24 journaled in a fixed stand- 55 ard 70 (Figs. 1 and 2). The arrangement is such that either the one or the other of the pawls can move its ratchet but never both simultaneously; in addition, when one of the pawls engages its ratchet the disengagement of the other is brought about in the following manner: The pawls 20, 21 are 60 yielding held in their positions for the time being by the leaf springs 32, 33 with the aid of nuts 37, 38 mounted on the pull- 65 rods 35, 36. The bottom ends of the pull-

rods 35, 36 are pivoted to one-armed levers 40 (Figs. 1 and 2) mounted on an axle 41; a torsion spring 46 about the axle 41 tends to hold the levers 40 in their lower positions and the pawls 20, 21 in the position represented in Fig. 1. The axle 41 can be rotated through the medium of a pin 47 and a lever 42 against the tension of the spring 46 by a key 48 used for starting justification, the two rods 35, 36 being driven upward and 75 reversing the positions of the pawls 20, 21. After the key 48 has been released the pawls 20, 21 are secured in their reversed positions by means of a bell-crank lever 51, 52 which is fulcrumed on the pin 58, and which tends 80 to move in the direction of the arrow (Fig. 2) through a spring, not shown, and engages a projection 43 on the lever 42 until it is released by the depression of a second or carriage-returning key 49 by means of 85 the pin 50 engaging the other end 51 of the bell-crank. The rotation of this axle 41 electrically connects the two contact-pieces 56, 57 not only together by means of the resilient contact arm 45 mounted on and in- 90 insulated from said axle, but also with a conductor 59. Further, a similar switch 54, 55 is arranged below the carriage-returning key 49. The feed action of the pawls 20, 21 is due to their being fixedly journaled in the 95 stationary frame, whereas the ratchet wheels 5, 6 mounted on the plates 2 move downward when these plates are rocked, and consequently the pawl at that moment in its operating position engages behind the next tooth 100 of the ratchet wheel, and on the backward movement of the frame-plates 2 and the upward movement of the ratchet wheels 5, 6, one of the latter is rotated one tooth. In 105 order to insure that the pawls properly engage and to prevent the ratchet wheels from being overthrown I arrange on one of the plates 2 (Fig. 1) stops 27, 28, 29, 30, which 110 coact with the points of the pawls 20, 21 and with set-screws 25 threaded into the latter.

The frame comprising the plates 2 is rocked in one direction through the medium of a catch 61, pivotally carried by brackets 63, by a lever 60 which is mounted to rock about an axle 87 (Fig. 2) and is actuated by 115 the working shaft 85 of the machine through the medium of a cam 89 and an antifriction roller 86, and the frame is rocked in the opposite direction by two helical springs 64, 65, one of which is attached to a frame-plate 120 2 and the other to the lever 60.

A bar 73 having slots 77 is slidable on the pins 71, 72 mounted on the standard 70. The left end of this bar is formed as a rack 78 and its right end as a grip 76; as seen in 125 Figs. 1 and 4, a spring 75 tends to draw the bar into its left-hand position. When the left end of the frame-plates 2 is moved downward, the ratchet wheel 5 engages with the rack 78 (Fig. 4). For this purpose a 130

lever 82, fulcrumed on a pin 81 on the standard 70, bears in its normal position against a stop-pin 83 owing to the action of the leaf spring 84, and also against the right end 60' 5 of the lever 60 (Fig. 2). On the lever 82 being depressed, not only is the lever 60 lowered, but also, owing to the catch 61, the left portion of the frame comprising the plates 2, and the ratchet wheel 5 is brought 10 into engagement with the rack 78. By pulling the grip 76 the ratchet wheel 5 can now be rotated as far as the slots 77 in the bar 73 will permit; the lengths of these slots are made such that the piece of the band fed 15 through the slit of the punching device 7, 8, 15 is just sufficient for accommodating the justification symbols.

The above-described apparatus operates as follows: The register band 100 to be 20 punched and having feed holes 100' (Fig. 5) at both sides, is first introduced into the bottom part of the slit in the punching device 7, 8, 15 (Fig. 3), then placed snugly around the guide 22 and finally conducted 25 back through the top part of the slit and around the upper feed wheels 13, 14. The writing and punching of the text is then begun, the pawl 21 being engaged and the pawl 20 disengaged from its ratchet wheel 5 30 and 6 respectively; therefore after each perforation only the ratchet wheel 5, *i. e.* the text feed-mechanism is driven, while the second ratchet-wheel 6, *i. e.* the justification feed-mechanism, remains at rest. While writing, 35 therefore, the free loop of paper II (Fig. 3) is formed.

The band is punched in the following manner: On the keys of the machine being depressed, the stop-levers 18 pivoted below 40 the punches are slightly rocked as soon as the working shaft 85 (Fig. 2) is released. The lever 60, the frame-plates 2 and the register band are moved downward, and those punches 15 whose pushers 17 abut 45 against the rocked stop-levers 18 pass through the paper band into the matrices in the upper portion 8 and produce the required perforated symbols. When the frame-plates 2 move upward, as mentioned 50 above, not only the feed wheels 11, 12 but also the text feed mechanism and the lower portion of the strip are fed forward.

Referring to Fig. 5, as soon as the end of the symbolically represented first line is 55 reached by striking and punching the letter "e" of the last word "welche", the justification symbol must be perforated. At this moment the front end of the band designated (X) is located at the punching position 60 in the upper part of the slit under the top part 8 containing the matrices. The key 48 for starting justification is now depressed, whereby two error symbols, each consisting of six holes, are punched into the upper and 65 lower portions of the band, one being at the

first place marked (X) and the other at the similarly marked place immediately behind the letter "e"; the two pawls 20, 21 are simultaneously reversed owing to the operation of the levers 40 and the draw rods 35, 70 36, and the bell-crank lever 51, 52 locks the pawls 20, 21 in this position. When the frame-plates 2 rock back after the error symbol has been punched the text feed-mechanism 5, 21, 11, 12 remains stationary, 75 while the justification feed-mechanism 6, 20, 13, 14 feeds the still unpunched part of the strip marked "W" into the position below the top part 8 containing the matrices. A second key, not shown, situated behind the 80 key 48 and used for starting justification is now depressed and causes a carriage-return symbol to be punched at the above-mentioned place marked "W" in the band. A switch, not shown, which is out of use during 85 the whole punching operation, prevents however, the return of the carriage taking place precisely at this moment. The purpose of this symbol is to hold in its position the shortage indicating device influenced by the 90 end position of the carriage, and nevertheless to allow the carriage-return symbol to come into operation before the justification symbol in the register band when the working machine is subsequently automatically 95 controlled by the register band. Another key marked "Space clutch" is then depressed, and afterward for the space value that key which corresponds to the value ascertained and indicated by a space-counting 100 mechanism when the line is symbolically written, and which is designated by a special type, for example "b". The space-clutch symbol "S" and then the space value symbol, in this case, "b" are hereby produced in 105 the band. The next key to be depressed is to be marked "Shortage clutch", whereupon the shortage value is punched by striking that key which corresponds to the value indicated by a shortage counter, and likewise 110 represented by a type, in the present instance the letter "n". These perforated symbols are to be seen on the band shown in Fig. 5 at the parts marked "F" and "n". The carriage can now be actually returned, 115 this being brought about by depressing the key 49 marked "Carriage return", the result being that an error symbol is punched in the band at the place marked (X) beyond that marked "n"; the feed mechanism is simultaneously unlocked owing to the release of the bell-crank lever 51, 52, so that after the band has been punched, the pawls 20, 21 are reversed after the frame of the punching device, *i. e.* the lower part 7 and of the upper 120 part 8, has moved upward. Accordingly, the part of the band marked with the error symbol (X) remains stationary in the top half of the slit, while that part of the band marked "W" (after the word "welche") 130

4
moves into the punching position. The actual return of the carriage is brought about, in spite of an error symbol being punched when the key 49 is depressed, by a pin 53, insulated from the latter, closing the switch 54, 55, and thus connecting an electromagnet, which controls the return of the carriage, to that segment of a controlling collector controlling the currents in the machine which corresponds to the error symbol. The open places seen in the strip beyond the justification symbols in Fig. 5 are provided in order to make inoperative any errors which may occur in reading or punching these symbols and to afford space for the insertion of the correct substitute symbols.

Before commencing to write a new line, the free loop must first be drawn out and be prepared for a new justification symbol, this being effected as follows: The punching frame comprising the two plates 2 is depressed by means of the lever 82 and the feed mechanism 5, 11, 12 is actuated by pulling the grip 76 of the bar 73 (Figs. 1 and 4), whereby the band is fed forward ten steps. The lever 82 and the grip 76 are then released, and the loose band is drawn taut around the guide bar 22 into the position 1 by pulling the end of the band leaving the justification device 6, 13, 14. In this manner an unperforated piece of band is brought into the slit and the band is ready for a new line.

When writing title lines which have to be subsequently inserted in the middle of the column when the band is used in a type-setting or type-casting machine, the operation is as follows: The writing is begun like an ordinary line at the left edge of the column and the length of the title line is read off on a scale on the paper carriage, whereupon the size and number of the spaces which correspond to this length of title line and are necessary for its being placed centrally are ascertained from a table and are then punched, just like justification symbols, in the band in the loop provided for justification. In this manner these central symbols come into action before the text symbols in the working machine which is to be controlled by the band. The object of the contact device 45, 56, 57, 59 (Fig. 2) is, when punching justification symbols which may not contain a sixth hole, to prevent any printing or feed taking place during the entire justification period, this being brought about by closing special circuits when the key 48 is depressed.

It may be noted that various sizes of spaces, *e. g.* half, normal and starting spaces, 60 must be used, and due regard must be paid to them in the tables required for writing the title lines so that it can be seen how many spaces of each kind must be punched for a predetermined length of title line. In the 65 case of particularly short title lines in long columns numerous starting spaces are needed, which cannot under all circumstances be accommodated in the loop of band provided for the reception of the justification symbols. In such cases an indication must be given in the tables up to what length of title line the normal justification loop suffices, or what lengths necessitates the text feed-mechanism being operated a second time by 70 displacing the grip 76 twice at the beginning of the line, in order to obtain a longer justification loop. In such a case, before beginning such a particularly short title line its length must be approximately estimated in 75 order to learn from the table whether the loop has to be formed by one or two displacements. In doubtful cases the larger loop will be made.

What I claim is:

1. A method of making register bands having justification symbols, which consists in bending the band into a loop, in punching holes representing one line of the text in the superposed parts of the band, the front 90 end of the band being held stationary while the part beyond the loop is fed, and in then punching justification symbols for the last line of the text, the front end of the band being fed while the part beyond the loop is 95 held stationary.

2. A method of making register bands having justification symbols, which consists in bending the band into a loop, in punching holes representing one line of the text 100 in the superposed parts of the band, the front end of the band being held stationary while the part beyond the loop is fed, and in then punching justification symbols for the last line of the text, the front end of the 105 band being fed while the part beyond the loop is held stationary, and in punching an error symbol in both that part of the band held stationary while punching the holes representing the line of text and also in that 110 part of the band held stationary while punching the justification symbols.
